UNITED STATES PATENT OFFICE.

JOHN S. EAGAN, OF PROVIDENCE, RHODE ISLAND.

CURTAIN FIXTURE.

Application filed January 14, 1926. Serial No. 81,211.

My invention relates to brackets adapted for use in supporting the flat type of curtain rod comprising a flat body portion with inturned or U-shaped longitudinal flanges, 5 the latter being provided near their ends with slots or holes for facilitating engagement with portions of the bracket.

In this type of fixture it has heretofore been attempted to employ upon the bracket 10 a hook projecting from within the upper flange upwardly through the hole therein with the result that the exteriorly projecting hook end prevented sliding the curtain to the wall, thus exposing the end of the rod.

An essential object of this invention is to remedy this defect. A further object is to facilitate the tilting of the rod during its engagement and disengagement; to afford an efficient guide and insure a smooth rolling 20 movement of the rod during these operations; and to attain these ends in a strong and inexpensive structure.

To the above ends essentially my invention consists in such parts and in such combinations of parts as fall within the scope of the appended claim.

In the accompanying drawings which form a part of this specification and wherein like reference characters indicate like parts 30 throughout the views:—

Figure 1 is a plan elevation of my brackets attached to a wall and engaged by a curtain rod,

Figure 2, an enlarged section of the same 35 on line 2—2 of Figure 1, and

Figure 3, a fragmentary section on line 3—3 of Figure 1, showing in broken lines a position of the rod during its application to the bracket.

In the drawings 5 is a curtain rod of the flat flanged type which may be sectional or nonsectional. In this instance it comprises telescoping sections. The rod includes a flat intermediate portion or body 8 and inwardly bent oppositely directed U-shaped upper and lower flanges 9 and 10 provided respectively with longitudinal slots 11 and 12 near the rod extremities. As shown the end portions of the rod are disposed at right 50 angles to the central portion.

Each of my brackets for supporting the rod comprises an attaching or wall plate 14 having integral with one of its vertically disposed lateral edges, intermediate the length of the plate, a substantially horizontal flat arm 16 disposed in a plane at right angles to

the plate and provided upon an intermediate portion of its upper edge with a longitudinally disposed lug 17 provided upon its forward end with a curved shoulder 18, and 60 whose rear end forms a shoulder 19. From the shoulder 19 rearwardly to the plate 14 the upper edge of the arm 16 is downwardly curved to afford clearance of the rod end and to afford a guide 20 upon which the latter 65 may roll.

Below the arm 16, and integral with the plate and arm, and in the vertical plane of the latter, is a flat extension or ear 22 of less length than the arm 16 provided along the 70 forward portion of its lower edge with a downwardly directed rearwardly inclined or curved bearing portion 23, whose rear end forms a slight shoulder 24 intermediate the 75 length of the ear. From this shoulder to the plate 14 the lower edge of the ear is horizontally disposed as at 25.

In applying the end of the rod to a bracket the former, in an inclined position, is moved over the ends of the arm and extension until, as shown by broken lines in Figure 3, the end portion of the upper flange 9 is in a position behind the shoulder 19, and the end of the lower flange 10 engages the bearing portion 23 of the extension 22. The rod is next depressed to a horizontal position which movement forces the end of the flange 10 along the portion 23, over the shoulder 24 to snap into a position behind the latter. While the maximum 90 distance between the portion 20 and shoulder 24 is somewhat greater than the distance between the flanges 9 and 10 it will be understood that the resiliency of the latter permits the described movement. Final engaged position of the rod with the bracket is shown in full lines in Figure 3 with the lug 17 in the slot 11, and the shoulder 24 in the slot 12.

It is essential that the lug 17 be located 100 intermediate the length of the arm 16, since the portion of the arm in front of the lug is the support for the rod. The downwardly curved fulcruming surface 20 is important because it not only makes unnecessary the 105 use of a hook or tall projection upon the arm 16, but permits the employment of the lug 17 which, it will be noted, does not project substantially above the horizontal plane of the upper flange 9. For this reason the 110 curtain may readily slide over the rod up to the plate 14 and without impediment.

The surface 20 is further important because it furnishes a rolling fulcruming surface which facilitates the movement of the rod over the surface 23 with which it cooperates during engagement or disengagement of the rod.

I claim:—

In a curtain fixture, a curtain rod comprising a flat body and two lateral resilient flanges provided near their ends with slots, a bracket comprising a wall plate, a flat substantially horizontal arm integral with the plate, a longitudinally disposed lug upon an intermediate portion of the arm adapted to register in the slot of one flange with its upper edge in substantially the horizontal plane of the flange, the portion of the arm

between the lug and the plate being formed with a downwardly curved guide upon which the rod may roll when tilted, and the outer 20 portion of the arm being adapted to normally support said flange, a flat ear integral with the plate below the arm provided upon its free end with a downwardly and rearwardly inclined bearing portion for the second flange and adapted to cooperate with the guide when the rod is tilted, and a shoulder on an intermediate portion of the ear terminating the bearing portion and adapted to enter the slot in the second flange. 36

In testimony whereof I have affixed my signature.

JOHN S. EAGAN.
